UNITED STATES PATENT OFFICE.

CYRUS W. SALADEE, OF TORRINGTON, CONNECTICUT.

ROAD-CART.

SPECIFICATION forming part of Letters Patent No. 298,415, dated May 13, 1884.

Application filed August 2, 1883. (No model.)

To all whom it may concern:

Be it known that I, CYRUS W. SALADEE, of Torrington, Litchfield county, Connecticut, have invented certain Improvements in Road-
5 Wagons, of which the following is a specification.

My invention relates to that class of road-wagons in which the body is supported upon two wheels; and it consists in constructing the
10 same, as fully described hereinafter, so as to afford a desirable spring-platform with but few springs, and so as to hang the body low down without detracting from the efficiency of the
15 spring-platform.

15 In the drawings, Figure 1 is a side elevation of a road-wagon, showing my improvements. Fig. 2 is a plan, the body removed; Fig. 3, a view illustrating half front and rear elevations; Figs. 4 and 5, side elevations showing
20 modifications.

The axle E is a crank-axle, and the supporting spring or springs C are secured to the sunken portion, thereby lowering the height of the body. The spring C shown is an elliptic spring parallel to the axle, so that but one
25 spring supports the body below the seat; but two springs may be arranged, as shown in dotted lines.

30 The pole or shaft frame B may be of any suitable construction, and is pivoted at x to the axle. As shown in Figs. 1 and 2, the frame consists of the shafts and cross-piece B'. In

Fig. 4 a compound frame is shown, consisting of the shafts, cross-piece, and secondary frame
35 B', consisting of side bars, b, pivoted to the axle and constituting continuations of the shafts, which are pivoted at j thereto, and cross-bar h. In either case the shaft-frame is pivoted to the raised portions of the crank-
40 axle, and the spring-platform rests upon the sunken portion of the axle, thereby securing a stable support for the body. The body is supported at the front by a transverse spring,
45 D, arranged at any suitable point, so as to be supported by the shaft-frame and afford a rest for the body. In Fig. 1 the spring is suspended at the ends from the shaft-frame. In
50 Fig. 4 it rests on the cross-bar h of said frame, and in Fig. 1, in dotted lines, it is supported by a bar of the frame in front of the dasher.

In either case the arrangement permits the

body to be hung low down between the shafts and yet permits a free vertical play. I use an adjustable connection to vary the set of the body according to the inclination of the shafts. 55 Thus hangers H, suspended from the shafts, have adjustable bolts k, whereby the ends of the springs or spring-support may be set at different heights. In Fig. 4 the hanger is used as a connection between the two parts of the
60 shaft-frame.

By the construction above described I am enabled to hang the body low down, yet secure a desirable spring-platform, which cannot be done in that class of road-wagons illustrated in Letters Patent No. 183,225, granted to Thomas Snow, October 16, 1876, where the body and spring-platform are above the top of a straight axle. By connecting the shaft-frame to the upper part of the axle, I avoid 70 all tendency to turn the latter by the pull upon the shaft.

In Fig. 5 I show a construction whereby there is a flexible connection in the form of a curved spring, M, between each shaft and the 75 axle. The front springs are longitudinal to the body. The shaft has thus two elastic supports, and more effectually relieves the body from the motion of the shafts.

The flexible pivotal connection of the shafts 80 with the axle may be adopted in any of the constructions I have described and in many other forms of vehicles.

I do not limit myself to any special form of body, springs, or adjusting devices; but
85 I claim—

1. In a road-wagon, the combination of a crank-axle, body, intermediate spring-platform supported by the lower part of the axle, shaft-frame pivotally connected to the upper 90 part of the axle, and spring-connection between the shaft-frame and forward part of the body, substantially as set forth.

2. The combination, with the front spring-support, crank-axle, shaft-frame pivotally connected with the axle, body extending between the shafts, and front supporting-spring, of an adjustable connection whereby to alter the relative set of the body and shaft-frame, substantially as specified. 95

3. The combination of the crank-axle, body, rear supporting-spring, C, parallel to the axle

and connected to the depressed portion thereof, and front spring connected to the shaft-frame, substantially as set forth.

4. The combination of the axle, body-supported springs, and shaft-frame, consisting of two sections jointed together, the rear section jointed to the axle, and an adjusting device connecting the sections, substantially as described.

5. The combination of the axle, spring-supported body, shafts pivoted at the rear ends to

springs connected to the axle, and spring-connections between the front of the body and shaft-frame, substantially as described.

In testimony whereof I have signed my name to this specification in the presence of two subscribing witnesses.

CYRUS W. SALADEE.
